(57) **CLAIM**

The ornamental design for a cheek retractor device, as shown and described.

DESCRIPTION

FIG. 1 is a front perspective view of a cheek retractor device according to the present invention;

FIG. 2 is a rear perspective view of the cheek retractor device of FIG. 1;

FIG. 3 is a front view of the cheek retractor device of FIG. 1;

FIG. 4 is a rear view of the cheek retractor device of FIG. 1;

FIG. 5 is a first side view of the cheek retractor device of FIG. 1;

FIG. 6 is an opposite side view of the cheek retractor device of FIG. 1;

FIG. 7 is a top view of the cheek retractor device of FIG. 1; and,

FIG. 8 is a bottom view of the cheek retractor device of FIG. 1.

Any broken lines shown in the figures are for illustrative purposes only and form no part of the claimed design. The dash-dot-dash broken lines mark the boundary between claimed and unclaimed portions of the illustrated cheek retractor device.
